(No Model.)

A. J. PEAVEY

SCREW TAP.

No. 295,421.

Patented Mar. 18, 1884.

UNITED STATES PATENT OFFICE.

ANDREW J. PEAVEY, OF SOMERVILLE, ASSIGNOR TO HIMSELF AND EDWIN B. BUCKINGHAM, OF BROOKLINE, MASSACHUSETTS.

SCREW-TAP.

SPECIFICATION forming part of Letters Patent No. 295,421, dated March 18, 1884.

Application filed May 1, 1883. (No model.)

To all whom it may concern:

Be it known that I, ANDREW J. PEAVEY, of Somerville, in the county of Middlesex and State of Massachusetts, have invented certain 5 new and useful Improvements in Screw-Taps, of which the following is a full, clear, and exact description.

This improved screw-tap in substance is composed of an arbor, of a sleeve surrounding 10 said arbor, containing a series of radial screw-cutting dies, and of two sets of cams or scrolls, all so that by turning said arbor in one direction said screw-cutting dies will be forced outwardly, or from the center of said arbor, and 15 in turning said arbor in the other and opposite direction said screw-cutting dies will be drawn inwardly toward the center of said arbor, substantially as hereinafter described.

In the accompanying plate of drawings this 20 improved screw-tap is illustrated.

Figure 1 is a side view; Fig. 2, a cross-section on line 2 2, Fig. 1; Fig. 3, a central longitudinal section on line 3 3, Fig. 2; Fig. 4, a cross-section on line 4 4, Fig. 3; Fig. 5, a central longitudinal section on line 5 5, Fig. 2; Fig. 6, a cross-section on line 6 6, Fig. 1; Figs. 7 and 8, longitudinal sectional views, to be hereinafter particularly referred to.

In the drawings, A represents an arbor having along a portion of its length similar scrolls or cams or eccentric surfaces, B, relative to the axis of the arbor. These scrolls B are arranged at equal distances apart and regularly around the arbor, giving a series of shoulders 30 or abutments, C, between the innermost end, a, of one scroll and the outermost and next adjoining end, b, of another and the next scroll in the order of arrangement. The scroll portion of the arbor A, and at each end thereof, 35 has a collar, D, and each collar D has four scroll or cam slots, E, corresponding to the scrolls B of the arbor, and which latter scrolls, B, continued constitute the inside walls of said slots. These collars D are fastened to the arbor A by pins C, or otherwise, so as to be attachable and detachable at pleasure, and between them and surrounding the arbor is a sleeve, F, having along its length, for a portion thereof, radial slots G, at equal distances 40 apart, in each of which is located a screw-cut-

ting die, H, having an outer screw-cutting face or edge, d, and an inner smooth face or edge, f, to bear against a scroll, B, of the arbor A, and extensions g at each end, to enter into the cam or scroll slots of the collars D at 55 each end of the scroll portion of the arbor.

A screw-tap constructed as described, placed in the hole to be screw-tapped, is turned around therein in a direction for the scrolls of the arbor to force the screw-cutting dies outward and from the center or axis of the arbor, and thus secure the cutting of the screw-thread in said hole, as desired. Turning the screw-tap in the opposite direction to that above described secures, through the action of 60 the scroll-slots E upon either end of the screw-cutting dies, an inward movement of the said dies—that is, a movement toward the center or axis of the arbor—thus withdrawing them from action upon the hole.

The cam-slots E, at either end of the scroll-arbor, may be dispensed with; but it is preferable to use them, and to have one at each end, and to engage the cutting-dies with both of them, for the reason that by their action the 75 screw-cutting dies will be positively drawn in when the arbor is turned in the proper direction therefor.

A screw-tap made as particularly shown in Figs. 1 to 6, and to which figures the preceding description applies, owing to the fact that the screw-cutting dies are between the two ends of the tool and do not extend fully up to one end thereof, is not capable of screw-tapping a socket or hole closed at one end up to said end; 80 but in Figs. 7 and 8 a tool substantially of the construction hereinbefore described, but varying in some respects therefrom, is illustrated which is capable of screw-tapping a socket or hole closed at one end. In said Figs. 7 and 8 85 parts corresponding with those shown in the previous figures are lettered as before—as, for instance, A is the scrolled arbor. H are the radially-moving screw-cutting dies. F is the sleeve surrounding them, having vertical radial slots G for said screw-cutting dies H; and D is the scrolled collar for forcing the screw-cutting dies in toward the axis of the scrolled arbor. Each screw-cutting die extends to the extreme end of the scrolled arbor A, and, as 90

shown in Fig. 7, the surrounding sleeve F covers only a portion, *m*, of the length of each die H, and leaves the screw-cutting portion *n* of each exposed. The arbor has a peripheral 5 groove, *l*, which receives the internal annular collar, L, of the sleeve, and the sleeve has radial slots G, each of which receives the lug M of a screw-cutting die, H, and all so that the sleeve and the dies are retained upon the arbor, and yet as the arbor is turned, forcing 10 by its scrolls E the cutting-dies outward or allowing them to travel inward, said sleeve is free to accommodate itself to such movement of the dies by turning with the dies 15 upon the arbor. The scrolled collar D loosely surrounds the sleeve F, and has its scrolls to force the dies inward located therein in suitable position to act upon the outer ends, *o*, of the lugs M of the dies before referred to, said 20 lugs being made of suitable radial length therefor. Said collar is screwed upon the arbor and there fastened by a check or set nut, *s*, also screwed upon the arbor.

In Fig. 8 the sleeve F, having radial slots 25 G, surrounds the cutting-dies H in their portion having cutting-edges, and also in their straight portions, substantially the same as in the screw-tap of the particular construction shown in Figs. 1 to 6, inclusive.

30 The sleeve and also the dies are retained upon the arbor by a cap-plate, N, fastened by a screw, *p*, to the extreme end of the arbor A. The cutting-dies extend across the edge or periphery of this cap-plate N, and at such 35 part are cut out, as at *q*, on their inner edge; and the cap-plate is of a suitable size or diameter to allow the dies their desired move-

ment outward from the action thereon of the scrolls of the arbor A, and their desired movement inward from the action thereon of 40 the scrolls or cam-slots of the collar D, attached to or a part of the arbor, said collar being at the inner end of the sleeve.

In all the forms of tools which have been illustrated and described it is obvious that 45 there are the same separate elements or parts, and that, except slight modifications in construction to accommodate said elements or parts to the end to be attained, they are combined and arranged and operate together in 50 substantially the same manner.

Having thus described my invention, what I claim, and desire to secure by Letters Patent, is—

1. A screw-tap composed of an arbor, A, 55 carrying a cam-slotted collar or collars, D, and of a slotted sleeve, F, having screw-cutting dies H, constructed and arranged together substantially as described, for operation as specified. 60

2. A screw-tap composed of an arbor, A, having scrolls B, and a cam-slotted collar or collars, D, and of a slotted sleeve, F, having screw-cutting dies H, constructed and arranged together substantially as described, for 65 the purpose specified.

In testimony whereof I have hereunto set my hand in the presence of two subscribing witnesses.

A. J. PEAVEY.

Witnesses:

EDWIN W. BROWN,
W. S. BELLOWES.
